US0D1008663S

(12) **United States Design Patent** (10) **Patent No.:** **US D1,008,663 S**
(45) **Date of Patent:** **** Dec. 26, 2023**

(54) **MINI ROLLER**

- (71) Applicant: **The Sherwin-Williams Company**,
Cleveland, OH (US)
- (72) Inventors: **Charles T. Buckel, Jr.**, Warrensville
Hts., OH (US); **Michael C.**
Lambertson, Jr., Warrensville Hts., OH
(US); **Connie M. McKinney**, Cleveland,
OH (US); **William Pavilonis**,
Cleveland, OH (US)
- (73) Assignee: **The Sherwin-Williams Company**,
Cleveland, OH (US)

(**) Term: **15 Years**

(21) Appl. No.: **29/859,907**

(22) Filed: **Nov. 15, 2022**

(57) **CLAIM**

The ornamental design for a mini roller, as shown and described.

DESCRIPTION

FIG. 1 is a perspective view of a first embodiment of a mini roller showing our new design;
FIG. 2 is a first side view thereof;
FIG. 3 is a second side view thereof;
FIG. 4 is a bottom side view thereof;
FIG. 5 is a top side view thereof;
FIG. 6 is a back view thereof; and,
FIG. 7 is a front view thereof.

The broken lines illustrate portions of a mini roller that form no part of the claimed design.

1 Claim, 5 Drawing Sheets
